ABSTRACT OF THE DISCLOSURE

An electrical signal storing device having on one side of its charge storing layer, an electroluminescent layer sandwiched between two sets of grids of gold conductors, wherein signals applied between the grids in each set cause the electroluminescent layer to emit light and produce, via a photoconductive layer, a signal representative charge pattern on the charge storing layer, and having on the other side of its charge storing layer a second electroluminescent layer sandwiched between two further sets of grids between which signals are applied to cause the electroluminescent layer to emit light and read off, via a second photoconductive layer, signals stored on the charge storing layer.

This invention relates to electrical signal storing devices and has for its object to provide improved, relatively simple and compact storing devices of large capacity and reasonably fast access.

According to this invention in its broadest aspect an electrical signal storing device comprises an electrical charge storing insulating layer, an electroluminescent layer, a photoemissive layer between said insulating layer and said electroluminescent layer, and means actuatable by signals to be stored for causing selected small portions of said electroluminescent layer to emit light, the whole arrangement being such that light emitted from said selected small portions of the electroluminescent layer cause photoemission from the corresponding small portions of the photoemissive layer the resultant depletion currents being utilised to produce signal representative charges on said insulating layer. The charge-storing insulating layer may be a partially laterally conductive glass layer as normally employed as the charge storing glass membrane or sheet of the target of a television camera tube of the Image Orthicon type.

In a preferred form of storing device in accordance with the invention the insulating layer is opaque to light emitted from the photoemissive layer and there are provided, in addition to the layers already mentioned, a second electroluminescent layer on the side of said insulating layer remote from the first mentioned electroluminescent layer, a photoconductive layer between said second electroluminescent layer and said insulating layer, and electrical means for causing selected small portions of said second electroluminescent layer to emit light thereby causing corresponding small portions of the photoconductive layer to become conductive and provide paths to an output circuit for charges stored on the corresponding small portions of said insulating layer.

The electroluminescent, photoemissive and photocon-

2

ductive layers may each be a continuous layer but preferably they are of so-called "dot mosaic" structure.

Light emission from selected small areas of an electroluminescent layer provided in accordance with this invention is preferably produced by providing said layer with sets of conductors on opposite sides thereof, the conductors of one set crossing (in projection) those of the other and applying potential between two selected conductors, one in each set, to cause light emission from the small layer portion of said electroluminescent layer in the region of the shortest path between the two selected conductors.

A preferred embodiment of the invention comprises a central layer of electrical charge storing material (such as the electrical charge storing glass commonly employed in the target structure of a television camera tube of the Image Orthicon type); a layer of photoelectric material deposited on one side of the central layer; a layer of photoconductive material deposited on the other side of said central layer; a pair of light-transparent sheets of metal film one on the outer side of the photoelectric layer and one on the outer side of the photoconductive layer; a pair of light transparent insulating spacers, one on each of the outer sides of the two metal film sheets; two grids each of transparent parallel metal film conductors one on each of the outer sides of the said spacers; a pair of electroluminescent layers one on each of the outer sides of said two grids; two further grids of parallel conductors one on each of the outer sides of the electroluminescent layers, the grids which are on opposite sides of the same electroluminescent layer being composed of conductors which (in projection) cross one another; a pair of insulating outer support and protecting sheets, one on each of the outer sides of the said two further grids; and connection means to the individual conductors of the grids and to the metal sheets.

The invention is illustrated in the accompanying in which FIGURE 1 is a cross-sectional schematic view showing the nature of the construction of a preferred embodiment of the invention and FIGURE 2 is a diagram showing the method of connection of the conductors of two grids on opposite sides of one of the electroluminescent layers in FIGURE 1. It is emphasized that both figures, but especially FIGURE 1, are purely schematic, no attempt being made in FIGURE 1 to show either the actual or the relative thicknesses of the various layers and conductors therein.

Referring to FIGURE 1, and starting with the left hand side of that FIGURE 1 is a glass supporting and protecting sheet, on the inner side (right hand side in FIGURE 1) of which is a deposited grid 2 of straight metal conductors which run parallel to one another. On the inner side of this grid is a layer 3 of electroluminescent material on the inner side of which is deposited grid 4 of light transparent thin straight metal film conductors—for example of thin deposited gold—running at right angles to the conductors of the grid 2. On the inner side of the grid 4 is a light transparent insulating spacer 5, e.g. of glass, on the inner face of which is a light-transparent conductive metal sheet film 6 e.g. of thin deposited gold. On the inner face of this sheet is a layer 7 of photoemissive material the inner face of which is on the adjacent face of a thin layer 8 of electric charge storing material. The member 8 may be a thin sheet or membrane of glass, on the inner face of which is a light-transparent

brane of the target of a television camera tube of the Image Orthicon type. Separate external connections are provided for the sheet conductor 6 and for the individual conductors of the grids 2 and 4.

The parts of the device as so far described constitute the parts which are employed to produce on the layer 8 a stored charge pattern representative of signals to be stored. If a signal to be stored is applied, in the form of a pulse of suitable value, between a selected conductor of the grid 2 and a selected conductor of the grid 4, then a small portion of the layer 3 lying in the shortest path between the two selected conductors i.e. in their cross over region (in projection) will emit light which, passing through the grid 4, the spacer 5 and the sheet 6 will cause photoemission from the corresponding small portion of the layer 7. A positive potential is maintained across the said layer 7 by a suitable potential applied to the conductive sheet 6. Accordingly the photoelectrons will be carried away and the depletion current from the photo-emissive material of the layer 7 will cause an electrical charge to be produced on and stored by the correspondingly small portion of the storage sheet 8. Thus, by applying signal potentials between different selected pairs of conductors, one conductor of any pair being in the grid 2 and the other being in the grid 4, a signal representative charge pattern can be produced on the insulating layer 8 which acts as the store. FIGURE 2 shows diagrammatically parts of the grids 2 and 4 on opposite faces of the electroluminescent layer 3. The incoming signals to be stored are applied between selected conductors by means known per se, indicated as constituted by logic control arrangements L1 and L2 to which the conductors are connected. Thus, if a suitable pulse is applied between the conductor marked X and the conductor marked Y in FIGURE 2, light, will be emitted from the small portion of layer 3 indicated by the letter Z.

Signals stored on the layer 8 could be picked off in various different ways. It would, for example, be possible to pick them off by scanning the right hand side (in FIGURE 1) of layer 8 by a cathode ray. In the preferred embodiment of FIGURE 1, which embodiment is much more compact and simpler than any arrangement involving cathode ray scanning would be, the stored signals are picked off by means of an arrangement somewhat similar to that used for producing them. Referring again to FIGURE 1 the layer 8 is made of light opaque material and on its outer face (right hand face in FIGURE 1) is a layer 9 of photoconductive material. On the outer face of layer 9 is a sheet 10 of thin, light transparent metal film, e.g. of thin deposited gold. On the outer side of the sheet 10 is a second light transparent insulating spacer 11, e.g. of glass, on the outer side of which is a grid 12 of thin, straight, parallel, light transparent metal film conductors. On the outer side of the grid 12 is a second electroluminescent layer 13, like the layer 3, with a grid 14 of straight parallel conductors on its outer face. The conductors of this grid run at right angles to those of the grid 12. Finally, on the outer face of the grid 14 is a second supporting and protecting sheet 15 like the sheet 1 and separate connections are provided to the conductors of grids 12 and 14 and to the conductive sheet 10.

To read off a signal stored on the layer 8, a reading pulse from a suitable source (not shown) is applied between the appropriate selected pair of conductors, one in the grid 12 and the other in the grid 14. This causes light emission from a selected small portion of layer 13 in the neighbourhood of the cross-over point of the selected pair of conductors and the correspondingly small portion of the photoconductive layer 9 becomes conductive. Output is taken from the conductive sheet 10, and it will be seen that, if a charge is present in the small portion of layer 8 corresponding to the illuminated small portion of layer 9, the output signal will be representative of that charge. Stored signals are thus taken off from

layer 8 by suitably pulsing different selected pairs of electrodes (one in grid 12 and the other in grid 14) by means of a circuit arrangement which it is not necessary to illustrate since it is, practically speaking, the counterpart of that of FIGURE 2.

Each of the layers 3, 7, 9 and 13 may be a continuous layer but in the interests of improved resolution, it is preferred to form them, in manner known per se, as dot mosaic structures rather than as continuous films.

The pick-up control circuit for taking off stored signals may, if desired, incorporate facilities for "re-writing" output signals back into the store when required.

The illustrated store device is exceedingly compact and of high capacity. It is believed that, in practice, it will be able to store as many as a million "bits" in a store of square form on a side of only about 12 inches.

I claim:

1. An electrical signal storing device comprising an electrical charge storing insulating layer, an electroluminescent layer, a photo-emissive layer between said insulating layer and said electroluminescent layer, and means actuatable by signals to be stored for causing selected small portions of said electroluminescent layer to emit light, the whole arrangement being such that light emitted from said selected small portions of the electroluminescent layer cause photoemission from the corresponding small portions of the photoemissive layer the resultant depletion currents being utilized to produce signal representative charges on said insulating layer and wherein the insulating layer is opaque to light emitted from the photoemissive layer and there are provided, a second electroluminescent layer on the side of said insulating layer remote from the first mentioned electroluminescent layer, a photoconductive layer between said second electroluminescent layer to emit light thereby causing corresponding small portions of the photoconductive layer to become conductive and provide paths to an output circuit for charges stored on the corresponding small portions of said insulating layer.
2. A device as claimed in claim 1 wherein the charge storing insulating layer is a partially laterally conductive glass layer as normally employed as the charge storing glass membrane of the target of a television camera tube of the Image Orthicon type.
3. A device as claimed in claim 1 wherein the electroluminescent, photoemissive and photoconductive layers are of so-called "dot mosaic" structure.
4. A device as claimed in claim 3 wherein, in order to produce light emission from selected small areas of an electroluminescent layer said layer is provided with sets of conductors on opposite sides thereof the conductors of one set crossing (in projection) those of the other and applying potential between two selected conductors, one in each set, to cause light emission from the small layer portion of said electroluminescent layer in the region of the shortest path between the two selected conductors.
5. A device as claimed in claim 4 comprising a central layer of electrical charge storing material; a layer of photoelectric material deposited on one side of the central layer; a layer of photoconductive material deposited on the other side of said central layer; a pair of light-transparent sheets of metal film one on the outer side of the photoelectric layer and one on the outer side of the photoconductive layer; a pair of light transparent insulating spacers, one on each of the outer sides of the two metal film sheets; two grids each of transparent parallel metal film conductors one on each of the outer sides of the said spacers; a pair of electroluminescent layers one on each of the outer sides of said two grids; two further grids of parallel conductors one on each of the outer sides of the electroluminescent layers, the grids which are on opposite sides of the same electroluminescent layer being composed of conductors which (in projection) cross one another; a pair of insulating outer support and protecting sheets, one on each of the outer sides of the said two further grids; and connection means to the indi-

vidual conductors of the grids and to the metal film sheets.
